UNITED STATES PATENT OFFICE

2,459,208

MODULATION CONTROL SYSTEM

Paul Gerhard Wulfsberg, Cedar Rapids, Iowa, assignor to Collins Radio Company, Cedar Rapids, Iowa, a corporation of Iowa

Application August 23, 1944, Serial No. 550,793

3 Claims. (Cl. 179—171)

1

My invention relates broadly to transmission systems and more particularly to a circuit arrangement for maintaining a high percentage of modulation in order to provide a maximum of intelligibility in telephonic transmission.

This application is a continuation-in-part of my application Serial No. 457,370, filed September 4, 1942, for Volume limiter circuit, now Patent 2,372,243, dated March 27, 1945.

One of the objects of my invention is to provide a circuit arrangement for a modulation system in which a substantially constant modulation level is maintained despite changes in input level, amplifier gain or modulation transformer voltage drop due to loading effects of the associated power amplifier of the transmitter.

Another object of my invention is to provide a circuit arrangement for an amplifier modulator unit in a modulated signal transmission system in which a control voltage developed in the unit is utilized to compensate, by an automatic change in gain through the system, all effects tending to change the modulation level.

A further object of my invention is to provide a circuit arrangement for a modulation control system in which a control voltage is derived from the point at which the modulating voltage is generated and utilized for compensating for any effects tending to change the modulation level.

Other and further objects of my invention reside in an electronic gain control system actuated by the modulating voltage for holding the modulation level constant as set forth in the specification hereinafter following by reference to the accompanying drawing which diagrammatically shows the circuit arrangement of my invention.

In radio transmitting equipment, it is important to maintain a high percentage of modulation in order to provide a maximum of intelligibility. Overmodulation, on the other hand, is undesirable because of spurious radiations, distortion and overloading of components. The requirement, then, is to provide some automatic means of maintaining a high average percentage of modulation without causing overmodulation.

A number of methods have been proposed to solve this problem. Among them are various peak limiters and volume compressors designed to secure a desired input-output level characteristic. These are effective when the equipment is operating under fixed conditions where they may be adjusted so as to not exceed the audio level to the modulator necessary for 100% modulation. Whenever the power amplifier is subject to variable loading, these systems of audio control are not effective.

In my aforesaid Letters Patent 2,372,243 of March 27, 1945, I have shown a volume limiting circuit. In the present invention this limiter is applied to modulation control by taking the con-

2

trol voltage from the point at which the modulating voltage is generated. A diode rectifier is connected to the output of the modulation transformer through an insulated winding. The D. C. output from this diode is proportional to the audio voltage across the modulation winding. This is true because of the tight coupling that exists between two windings on a common iron core.

It is necessary to supply a peak audio voltage equal to the plate voltage of the power amplifier for 100% modulation. This voltage is subject to variation as the power amplifier load changes, assuming constant audio amplifier gain. As the power amplifier draws increased current, increased gain is needed while for decreased loads a smaller gain is required.

This system using an electronic gain control actuated by the modulating voltage is very effective in holding the modulation level constant. The gain of the amplifier increases or decreases to provide more or less audio power as required by the power amplifier. It is possible with this automatic control to maintain a high level of modulation without danger of overmodulation.

Referring to the drawing in detail, the audio frequency input circuit leading from the audio frequency control channel such as a microphone circuit, program distribution system, television control circuit, facsimile system or telegraphic tone channel is indicated by reference character 1 connected through audio frequency transformer 2 to the input circuits of the single duo-triode 3. The duo-triode 3 includes cathodes 3a and 3a', control grids 3b and 3b' and anodes 3c and 3c'. Tube 12SL7 serves particularly well for the position 3. A fixed grid bias is obtained from the drop across the cathode resistors 4—5—6 in the biasing circuit 25 of the amplifier tube 7 as will be more fully explained hereinafter. In the embodiment described, tube 12A6 serves particularly well for the position 7.

The secondary winding 8 of input transformer 2 is paralleled by a resistance network constituted by resistors 9—10—11 and 12 symmetrically arranged and connected to ground at 14. Resistors 9 and 12, in the embodiment of the circuit of my invention employing the 12SL7 tube in the position 3, each have a value of 33,000 ohms while resistors 10 and 11 each have a value of 18,000 ohms. The opposite terminals of secondary winding 8 are connected to anodes 3c and 3c' through resistors 15 and 16, each of which in the embodiment described have a value of 68,000 ohms.

Balanced output circuits are connected to the anode circuits of tube 3 as shown, that is, primary winding 17 connects between anode 3c and tap 18 intermediate resistors 9 and 10 and primary winding 19 connects between anode 3c' and tap 20 intermediate resistors 11 and 12.

Primary windings 17 and 19 are closely coupled through iron core 21 with secondary winding 22 of the coupling transformer 23 which couples the output of the balancing tube 3 with the amplifier tube 7.

Secondary winding 22 of coupling transformer 23 connects at one end with control grid 7b of amplifier tube 7 and at the other end to tap 24 intermediate the cathode resistors 5 and 6 of the biasing circuit 25 connected between cathode 1a and ground 26 for applying the required operating bias to grid 7b of tube 7. In the embodiment of my invention as described, resistors 4 and 5 each have the value of 470 ohms while resistor 6 has the value of 600 ohms. Resistors 4, 5 and 6 are shunted by condenser 27 which in the embodiment described has a value of 25 mf. The fixed bias voltage for the grids 3b and 3b' of tube 3 is secured through tap 28 intermediate resistors 4 and 5 of biasing circuit 25 and through the resistor 29 of 4.7 megohms leading to the control grids 3b and 3b' of tube 3. The output circuit of tube 7 extends from anode 1c and shield grid 1d to the plate potential source indicated at 30 through primary winding 31 of audio frequency output transformer 32.

Transformer 32 has an iron core 33 and a secondary winding 34 wound thereon. A mid-tap 35 is provided in secondary winding 34 leading to the cathode circuit 36a and 37a of the push-pull modulator system which comprises tubes 36 and 37. In the embodiment of the circuit described I employ two 1625 tubes as the push-pull modulators. The control grids 36b and 37b of the push-pull modulators connect to opposite ends of the secondary winding 34. The path to the cathodes 36a and 37a from tap 35 includes the 150 ohm resistor 38 shunted by condenser 39 of 25 mf. capacity. The cathode circuit is grounded at the tap 35 as shown at 40.

The output of the push-pull modulator system includes a modulation transformer 41 having a secondary winding 42 divided into two symmetrical portions 43 and 44 with a mid-tap 45 therebetween. The portion of the secondary winding shown at 43 connects between mid-tap 45 and anode 36c while the portion of the secondary winding shown at 44 connects between mid-tap 45 and anode 37c. The intermediate grids 36d and 37d connect to the source of potential 30 and the mid-tap 45 of transformer 41 connects to the source of potential 57 from which the circuit is completed through ground connection 46 to the ground connection 48 returning to the cathode circuit 36a—37a through biasing resistor 38 and condenser 39.

The modulation transformer 41 has an iron core 47 and an output secondary winding 48 that leads to the power amplifier system and in addition there is a special insulated winding 49 wound on the transformer but substantially insulated therefrom by an insulation layer schematically designated at 50. The winding 49 serves to take control voltage from the push-pull modulator tubes 36—37 and impress this voltage upon the full wave rectifier. This full wave rectifier in the embodiment of my invention described herein is a 12H6 tube having an 0.5 mf. condenser 52 connected between the tap 53 on secondary winding 49 and the cathode circuit 54 of the full wave rectifier 51. The rectifier circuit is grounded at 55 thus establishing a circuit from the anodes 56 of the full wave rectifier 51 through ground 55 and ground 26 and 14 to the grid biasing circuit 25 of tube 7 and the electron discharge path

through tube 3. The path is completed from the cathode circuit 54 of full wave rectifier tube 51 through lead 56 extending to control grids 3b and 3b' of tube 3 and through resistor 28 and tap 28 and resistors 5 and 6 in grid biasing circuit 25 of tube 7. The biasing circuit to tube 3 is completed by the circuit that extends through biasing resistor 29 and resistor 4 of biasing circuit 25 to the cathodes 3a and 3a' of tube 3. Thus in addition to the fixed bias maintained on control grids 3b and 3b' by normal operation of bias resistor 4 in the grid cathode path of tube 3; and upon control grid 7b of tube 7 by the potential drop through resistors 4 and 5, a compensatory bias is impressed upon grids 3b and 3b' by the rectified control voltage supplied from the modulation transformer. A constant level will thus be maintained across the output winding 48 of the transformer. As a result of the co-action of the several portions of the circuit a constant modulation level is maintained despite changes in input level, amplifier gain, or modulation transformer voltage drop due to loading effects of the power amplifier of the transmitter. In other words, the control voltage is taken from a point in the circuit such that almost any effect tending to change the modulation level is compensated by an automatic change in gain through the system.

While I have described my invention in one of its preferred embodiments, I realize that changes in circuit arrangement may be made and I desire that it be understood that no limitations upon my invention are intended other than may be imposed by the scope of the appended claims.

What I claim as new and desire to secure by Letters Patent of the United States is as follows:

1. An amplification control system comprising a pair of balanced electron tube amplifier units each connected in push-pull circuit arrangement, a single electron tube unit including a cathode, a control grid and an anode with one circuit path interconnecting said cathode and control grid and another circuit path interconnecting said anode and cathode, a resistive circuit connected in both of said circuit paths, said unit coupling the output circuit of one push-pull amplifier unit with the input circuit of the other of said push-pull amplifier units, a bias control circuit connected between the first of said push-pull amplifier units and the resistive circuit in the circuit paths leading to the cathode of said single electron tube unit, a signal input circuit connected with the input circuit of the first of said push-pull amplifier units, a signal output circuit connected with the output circuit of the second of said push-pull amplifier units and a full wave rectifier system connected with the output circuit of the second of said push-pull amplifier units for superimposing on said bias control circuit compensatory biasing potentials for maintaining a substantially constant signal level at the signal output circuit.

2. An amplification control system comprising a pair of balanced electron tube amplifier units, each connected in push-pull circuit arrangement and each including cathodes with associated control grid electrodes and coating anodes, an electron tube system coupling the output of one of said balanced electron tube amplifier units with the input of the other of said balanced electron tube amplifier units said electron tube system including a cathode, a control grid, and an anode, a resistive circuit connected in series with said last-mentioned cathode, a tap on said resistive circuit connected with the grid electrodes of said

first-mentioned electron tube amplifier unit, means coupled with the output circuit of said last-mentioned pair of balanced electron tube amplifier units for deriving a biasing current therefrom, and a connection from said means to the grid electrodes of said first mentioned electron tube amplifier unit for impressing compensatory bias potential on said first mentioned grid electrodes in excess of the bias potential impressed upon each of said grid electrodes from the tap on said resistive circuit, a signal input circuit connected with the first of said electron tube amplifier units, and a signal output circuit connected with the last of said electron tube amplifier units.

3. An amplification control system comprising a pair of balanced electron tube amplifier units, each connected in push-pull circuit arrangement and each including cathodes with associated control grid electrodes and coacting anodes, an electron tube system coupling the output of one of said balanced electron tube amplifier units with the input of the other of said balanced electron tube amplifier units, said electron tube system including a cathode, a control grid, and an anode, a biasing connection leading to the grid electrodes of said first mentioned electron tube amplifier unit, a multiple tap resistor connected in series with said last mentioned cathode, an independent resistor, one of said taps being con-

nected with the biasing connection leading to said grid electrodes of said first mentioned electron tube amplifier unit through said independent resistor, means connected with the output circuits of said last mentioned pair of balanced electron tube amplifier units for deriving a biasing current therefrom and a connection from said means to the biasing connection leading to the grid electrodes of said first mentioned electron tube amplifier unit for impressing compensatory bias potential on said grid electrodes in excess of the bias potential impressed upon each of said grid electrodes from the tap on said multiple tap resistor, a signal input circuit connected with the first of said electron tube amplifier units and a signal output circuit connected with the last of said electron tube amplifier units.
